Application April 15, 1953, Serial No. 349,080

7 Claims. (Cl. 179—18)

This invention relates to signaling systems and particularly to pulse correction means for step by step machine switching telecommunication systems.

The object of the invention is economy and reliability of operation where difficult operating conditions jeopardize satisfactory functioning of switching apparatus.

It is known that in party line working, particularly where a line extends into a rural area and is heavily loaded, the pulses transmitted for controlling switching apparatus are subject to distortion and particularly to attenuation. The rate of pulsing may easily be maintained at any given standard, but the timing of the individual pulses depends on line conditions to the extent that pulses may be attenuated beyond a safe minimum and therefore lead to erratic operation of selector and connector switches. A satisfactory and economical method of insurance is what is known as a lock pulse circuit, that is, the use of a fast operating relay to respond to a pulse which thereupon locks in its operated position and remains locked under control of the stepping magnet to be operated by the pulse.

The present invention resides in a circuit arrangement for providing lock pulse operation in a selector switch and lock pulse repeating to succeeding switches constituting a pulse correcting circuit. A locking relay is provided in a selector switch and made responsive to all pulses transmitted to this switch, both those employed for setting the switch and those employed later for setting succeeding switches. The locking relay then causes the operation of a stepping magnet in the switch or another relay having the operating characteristics of a stepping magnet and the locking circuit is maintained until either the stepping magnet or the relay of like characteristics has become fully operated. Thus proper stepping of the selector or a succeeding switch may be insured if the pulse is long enough to operate the said fast operating relay even though it may be attenuated beyond the possibility of operating a stepping magnet.

A feature of the invention is a pulse correction means comprising a locking relay responsive to pulses and an unlocking means therefor having comparatively slow operating characteristics. The said locking relay is common to and operates in combination with a plurality of said unlocking means.

Another feature of the invention is a lock pulse arrangement for use in a selector switch comprising a common locking relay operating in combination with a local unlocking means in the form of a stepping magnet for local operations and with an unlocking relay for repeating pulses for distant operations, the said unlocking relay having operating characteristics equal to those of a stepping magnet.

Another feature of the invention is an economical circuit arrangement comprising a lock pulse relay employed in a mutually controlled circuit and at succeeding stages with the various stepping magnets of a switch and a pulse correction relay having operating characteristics equal to those of a stepping magnet.

Other features will appear hereinafter.

The drawings consist of two sheets having three figures, as follows:

Fig. 1 is a block diagram showing how Figures 2 and 3 may be placed to form a complete circuit diagram of a system including the selector switch of the present invention;

Fig. 2 is a schematic circuit diagram including a representation of a calling line, a line circuit therefor, an allotter, a line finder and a portion of the circuit diagram of the selector; and

Fig. 3 is the remainder of the circuit diagram of the selector.

The two sheets of drawings containing Figures 2 and

3, when placed as shown in Figure 1, provide a complete circuit diagram of the selector switch together with indications of a calling party line, line circuit therefor, an allotter and a line finder to extend the line to the selector. The selector is in its mechanical construction a conventional step-by-step selector, that is, it is equipped with four brushes, the tip brush 301, the ring brush 301, the sleeve brush 302 and the help sleeve brush 303. It is also equipped with an XX brush 304 and an X brush 305. When the selector is moved by the primary magnet 306 both the regular brushes T, R, S and HS and the control brushes XX and X move forwardly. When a given level has thus been selected, the secondary magnet 307 is operated and this moves only the regular brushes T, R, S and HS, the X and XX brushes remaining at the point where they were moved in the primary movement of the switch.

In the present circuit arrangement the X and XX brushes control various combinations for digit adding and digit cancellation, an arrangement of great value in small community dial offices where certain digits dialed may not be actually used but are useful for maintaining a uniform numbering scheme. Details of these connections will be given hereinafter.

Let it be assumed that a substation 200 on the line 201 makes a call. The line circuit 202 will be operated in conventional manner and through the allotter 203 a given line finder 204 will be caused to pick up the calling line and extend the connection into the selector circuit shown partly in Figures 2 and 3. When the call is made, the allotter will ground the starting wire causing the start relay 205 to operate and this will immediately place a bridge including the resistance 206 across the tip and ring conductors leading to the selector. This bridge will cause the operation of the CB calling bridge relay 207 in the selector over a path from ground, the source of dial tone 306, the springs 7 and 6 of the off normal switch shown in rectangle 307, armature 1 and back contact of the SH relay 208, armature 1 and back contact of the DA relay 308, armature 1 and back contact of the DC relay 309, armature 2 and back contact of the SW relay 310, springs 6 and 7 of the overflow contacts shown in rectangle 311, upper winding of the CB relay 207, the tip of the line, normal contacts of armature 1 of the SR relay 209, front contact and armature 2 of the ST relay 205, resistance 206, normal contacts of armature 1 of the SW relay 210, normal contacts of armature 2 of the SR relay 209 and thence through the lower winding of the CB relay 207 to battery. The CB relay operates and extends a connection from ground, armature 1 and its normal back contact of the PT relay 211, armature 1 and front contact of the CB relay 207, winding of the RD slow releasing relay 312 to battery. The RD relay, in operating, extends a ground from its front contact and armature 4 to the back sleeve wire 313 which is extended to the SW relay 210 and thence through armature 1 and front contact of the ST relay 205 to the starter wire. In conventional manner (not shown) the original

ground on the starter wire from the allotter 203 is now removed and the SW relay becomes operated in series with the ST relay 205, whereupon the T, R, S and HS conductors will cut through the line finder to the selector.

At the same time the RD relay 312 extends ground from its armature 2 and front contact to the lower biasing winding of the SR relay 209 and through springs 1 and 2 of the off normal set, shown in rectangle 312, through the upper winding of the XD relay 315 to battery. The SR relay does not become operated at this time but the XD relay operates. The circuit of the selector is now in a stable condition and will remain so until the calling subscriber dials.

By way of example, it will be assumed that the calling subscriber dials to a level in which the XX switch comes to rest on a terminal connected to the M wiring. In this case the CB relay 207 follows the pulses from the subscriber's dial and upon each such pulse places ground on its armature 1, on its back contact, thence through the armature 1 and front contact of the RD relay 312, armature 3 and front contact of the SH relay 208 (operated from armature 3 and front contact of the XD relay 315), the interrupter springs of the secondary magnet shown in rectangle 316, the overflow contacts shown in rectangle 317, the winding of the HA relay 318, through its armature 3 and back contact, through the interrupter contacts of the Z magnet shown in rectangle 319 to battery. The HA relay, which for the purposes of the present invention we may describe as a comparatively fast acting relay, now extends a circuit from ground, its armature 4 and front contact, the armature 10 and back contact of the SW relay 310, the alternate contacts of armature 7 of the XD relay 315, the winding of the primary magnet 306 to battery. The primary magnet operates in this circuit to follow the pulses from the CB relay 207. It should be noted, however, that if the pulse is foreshortened so that the HA relay might become deenergized before the primary magnet 306 could complete its operation, means is provided to prevent such an operation. Upon the operation of the HA relay 318 a locking circuit is established from ground, back contact and armature 1 of the PC relay 320, front contact and armature 2 of the HA relay 318, the interrupter springs of the primary magnet, shown in rectangle 321, and thence to the circuit for the energizing of the HA relay so that this relay, immediately it operates, becomes locked and will remain in this condition until the primary magnet 306 has completely operated. At this time the interrupter springs of the primary magnet, shown in rectangle 321, will open the locking circuit of the HA relay so that if by this time the pulse has terminated, the HA relay will release and by so doing will also release the primary magnet 306.

Upon the operation of the HA relay 318, a circuit is also established from ground, armature 4 and front contact thereof, armature 6 and front contact of the XD relay 315 and thence through the lower winding thereof to battery. As the switch takes its first step in the primary direction, the primary off normal contacts are operated, and those contacts shown in rectangle 314 open the circuit for the upper winding of the XD relay 315 so that this relay now depends on its locking circuit through its lower winding.

Thus the primary magnet 306 will respond to the separate pulses, whereas the XD relay 315 will respond to the train of pulses as a whole. At the end of this series of pulses, the XD relay 315 will release. Thereupon a circuit will be established from ground, front contact and armature 4 of the RD relay 312, back contact and armature 9 of the SW relay 310, armature 5 and back contact of the XD relay 315, the XX brush 304 now assumed to be resting on a contact to which the conductor 322 is connected so that this ground connection will be extended through springs 7 and 6 of the secondary off normal switch shown in rectangle 323, through the normal contacts of armature 6 of the SW relay 310 and thence over

the circuit hereinbefore traced for the energization of the HA relay 318. The HA relay becomes operated and extends a ground from its armature 4 and front contact over armature 10 and back contact of the SW relay 310, the normal back contact of armature 7 of the XD relay 315, through the winding of the secondary magnet 307 to battery. The secondary magnet operates and moves the brushes of the selector a first step in the secondary direction.

Upon the operation of the secondary magnet the circuit for the HA relay 318 is broken by the secondary interrupter contacts shown in the rectangle 316. The HA relay releases, in turn releasing the secondary magnet 317. The S brush 302, however, has moved to its first contact and if the line connected thereto is busy a ground now on the S brush 302 will be extended over the back contact and armature 2 of the PC relay 320, the armature 5 and back contact of the SW relay 310 to the circuit for the HA relay 318. The HA relay 318 and the Y magnet 307 will interact in their mutually controlled circuit and the brushes of the selector will be driven forward automatically until an idle line is found. At this time a circuit will be extended from ground, the front contact and armature 4 of the RD relay 312, the winding of the SW relay 310, springs 5 and 6 of the secondary off normal set 323 and thence to the winding of the HA relay 318. The winding of the SW relay 310 is comparatively high, whereas the winding of the HA relay 318 is comparatively low in resistance so that the SW relay becomes operated in this circuit and the HA relay remains unoperated. Upon the operation of the SW relay the circuit of the HA relay is opened and the SW relay 310 remains operated in a circuit including the alternate contacts of its armature 6, the resistance 324 to battery.

In this manner the calling line is extended through the armatures 1 and 3 of the SW relay to the tip and ring brushes 300 and 301 respectively to the succeeding circuit which may be another selector or it may be a connector.

The calling subscriber now dials another digit. The CB relay 207 responds to the pulses of this digit in the manner described and causes the operation of the HA relay 318. Since the SW relay 310 has now operated, a circuit is established from ground, armature 4 and front contact of the HA relay 318, armature 10 and front contact of the SW relay 310 to the winding of the PC relay 320 and thence to battery. The PC relay is one which has been adjusted to have the same operating characteristics as the primary magnet 306 or the secondary magnet 307. In other words, it is comparatively slow to operate so that it will not open the locking circuit of the HA relay 318 at its armature 1 and back contact until a stepping magnet in a succeeding circuit has had sufficient time to operate. It will be noted that the HA relay 318 has a means at its armature 1 and back contact for repeating pulses into the succeeding circuit. These pulses each consist of an opening of the circuit between the succeeding calling bridge relay and a bridge provided during dialing by the armature 2 and front contact of the SH relay 208 and during other periods by the upper winding of the SR relay 209.

Thus the HA relay 318 is common to the comparatively slow operating stepping magnet 306, the comparatively slow operating stepping magnet 307 and the comparatively slow operating relay 320.

When the called subscriber answers and reverses the line in the conventional manner, the current flow in the upper winding of the SR relay 209 will be reversed and this relay will respond, in turn reversing the current to the calling subscriber for conventional purposes.

While the various connections which may be made to the terminals traversed by the XX brush 304 and the X brush 305 are not included in the novel features of the present invention, these alternative wirings will be briefly disclosed. While it is assumed that the first two digits

to be dialed by the calling subscriber are those characterizing the particular community dial office in which this calling subscriber is located, then these two digits will be cancelled. In order to do this the N and V wiring will be applied to the terminals of the level dialed by the first digit. When the XX brush 304 and the X brush 305 come to rest on these terminals, a circuit will be established from ground, the V wiring connection to the corresponding terminal, the X brush 305, the back contact and armature 4 of the XD relay 315 (when this relay becomes released), the back contact and armature 4 of the DA relay 308, the armature 8 and back contact of the SW relay 310, the armature 2 and front contact of the CB relay 207, the armature 4 and back contact of the DC relay 309, thence through the winding of this relay to battery. The DC relay operates in this circuit and locks through the alternate contacts of its armature 4, thence in parallel through the back contact and armature 3 of the DA relay 308 and the back contact and armature 1 of the XD relay 315 to armature 4 and front contact of the RD relay 312.

At the same time ground on armature 4 of the RD relay will be extended through the back contact and armature 9 of the SW relay 310, armature 5 and back contact of the XD relay 315, the XX brush 304 to the terminal on which this brush now rests and which is connected to the N wire 325 through the front contact and armature 5 of the DC relay 309, now closed, the front contact and armature 5 of the RD relay 312 and thence through the springs 4 and 3 of the X off normal set shown in rectangle 326, the winding of the Z release magnet 327 to battery. Thus the switch is released and will return to its normal seized condition with the CB relay 207, the RD relay 312 and the XD relay 315 operated. The DC relay 309 will also remain operated.

The calling subscriber now dials the second digit of this number which designates his own office and in this case will reach a level characterized by the Z wiring. As the XD relay releases, a ground on armature 4 of the RD relay 312 will be extended through the back contact and armature 9 of the SW relay 310, the armature 5 and back contact of the XD relay 315, the XX brush 304 to a contact to which the Z wire 328 is connected so that this ground will now be extended through the front contact and armature 3 of the DC relay 309, the winding of the DA relay 308, the normal back contact of armature 2 thereof to the battery supplied through the Z interrupter springs shown in rectangle 319. The DA relay 308, in operating, locks in a circuit from battery to alternate contacts of its armature 2, its winding, its front contact and armature 3 to the ground on armature 4 of the RD relay 312. As the DA relay operates it will extend this locking ground through armature 3 and front contact of the DC relay 309, front contact and armature 5 of the DA relay 308, front contact and armature 5 of the DC relay 309 to the circuit for the release magnet 327 in the manner hereinbefore described.

As the switch releases the selector will again come into the condition awaiting another series of pulses. As the XD relay 315 operates, the locking circuit of the DC relay 309 is opened at the back contact and armature 1 of the XD relay 315 so that the DC relay releases. Now the calling subscriber may dial any given number whereupon with the DA relay 308 operated the switch will successfully make connection to an idle line in the wanted level. The idle line hunting operation will be started from ground, front contact and armature 4 of the RD relay 312, armature 3 and front contact of the DA relay 308, armature 3 and back contact of the DC relay 309, armature 2 and back contact of the XD relay 315, springs 7 and 6 of the off normal set shown in rectangle 323 and thence through the circuit hereinbefore described for the operation of the HA relay 318.

Various combinations to fit varying operating situations may be provided by the use of the Q, M, Z, N and

V wirings indicated in the lower righthand corner of Figure 3. Thus the N and V wiring on the first level to be dialed by a calling subscriber will cancel that digit, but allow the level to be used after a second added digit has been similarly cancelled. The Q and V wiring may be used on a level to be used before but not after the second added digit. The N wiring only is used on a level requiring busy tone if dialed before the first added digit, will be employed for digit cancellation after the first added digit and will allow the use of the level after the second added digit. The Q wiring will be used on a level requiring busy tone if such level is dialed before the first added digit and will allow the use of the level after the first added digit. The Z wiring is used only on levels reached by a second added digit and provide busy tone if this level is dialed before the first added digit. This wiring also provides for use of the level after the second added digit. The Z and V wiring is used on first or second digit adding levels with the use of all levels after being dialed the first time. The M wiring is used on a level to be used the first time dialed. If there is no wiring on a level then busy tone will be applied to the calling line if such level is dialed before the first added digit and the use of the level will be allowed after the second added digit.

If neither the DC relay 309 nor the DA relay 308 is operated by the first digit, as when the first digit sets the XX brush 304 on a terminal having no one of the Q, M, Z or N wiring connections and the X brush 305 on a terminal not having a V wiring connection, then there will be no way of starting the secondary or idle line hunting movement of the switch and the switch will remain as set in its primary movement. Thereupon the source of busy tone 321 will be connected through springs 5 and 6 of the X-ON off normal set shown in rectangle 307 and thence over the circuit previously traced through the upper winding of the CB relay 207.

If the first digit is to be immediately effective, then the DA relay 308 is operated to open the dial tone and busy tone circuit as by the use of the M wiring.

If but a single digit is to be added, that is dialed and then cancelled so that the second digit will successfully set the switch, then the Z and V wiring connections are used. The V wiring will cause the operation of the DC relay 309, the wiring will thereupon cause the operation of the DA relay 308 and thereafter the release of the switch. Upon the first pulse of the next digit the DC relay 309 will be released and this second digit will become effective.

If two digits are to be cancelled then the N and V wiring will be used so that on the first digit the DC relay 309 will be operated. If, on the second digit, the DA relay 308 is operated, as by the Z wiring, this digit will be cancelled and the DC relay is released, leaving only the DA relay 308 operated so that the third digit will be effective.

Thus a flexible arrangement is provided so that the selector may be adapted to various operating conditions.

What is claimed is:

1. In a telecommunication system, subscriber lines each having dial stations thereon, a selector switch for extending connections from said lines under control by said dial stations, said selector switch having a comparatively fast operating relay responsive to dial pulses transmitted from said dial stations, a locking circuit for said relay, a stepping magnet for said selector switch controlled by said relay, means controlled by said magnet for opening said locking circuit, means for repeating pulses transmitted to said fast operating relay, another relay having comparatively slow operating characteristics, said characteristics being like the operating characteristics of said stepping magnet, said other relay being under control of said fast operating relay and means controlled by said other relay for opening said locking circuit.

2. In a telecommunication system, subscriber lines each having dial stations thereon, a selector switch for

extending connections from said lines under control by said dial stations, said selector switch having a comparatively fast operating relay, a locking circuit for said relay, a plurality of stepping magnets and relays all having like operating characteristics, each of said magnets and relays having means for opening said locking circuit, said comparatively fast operating relay having control over each of said magnets and relays, means for switching said control of said comparatively fast operating locking relay to each of said magnets and relays in turn, and pulse repeating contacts controlled by said fast operating relay.

3. In a telecommunication system having dial station lines, selectors having switch stepping magnets responsive thereto and succeeding circuits and switches accessible to said selectors, means in said selectors for lengthening attenuated pulses transmitted from said dial station lines to said selectors and for repeating said lengthened pulses into said succeeding circuits consisting of a circuit arrangement including a stepping magnet responsive to pulses from a said dial station line having means to control the length of pulses transmitted thereto, a relay of characteristics like to those of said stepping magnet likewise responsive to pulses from a said dial station line and having means to control the length of pulses transmitted thereto and means responsive to an operation of said selector by said stepping magnet in extending a said dial station line to a said succeeding circuit and switch for transferring a connection between a said dial station line and said stepping magnet to a connection between a said dial station line and said relay having characteristics like to those of said stepping magnet.

4. In a telecommunication system having dial station lines, selectors having switch stepping magnets, succeeding circuits and switches accessible to said selectors, a calling bridge relay in each said selector, a stepping magnet in each said selector, said calling bridge relay and said stepping magnet being connected in a mutually controlling circuit, a repeating relay in each said selector for repeating pulses from a said dial station line to a said succeeding circuit and switch, said repeating relay having characteristics like to those of said stepping magnet and means responsive to the operation of said selector in extending a said dial station line to a selected succeeding circuit and switch for substituting said repeating relay for said stepping magnet in said mutually controlling circuit.

5. In a telecommunication system, subscriber lines each having dial stations thereon, a selector switch for extending connections from said lines under control by said dial stations, said selector switch having a control circuit including a comparatively fast operating relay responsive to dial pulses transmitted from said dial stations, a locking circuit for said relay, a stepping magnet for said selector switch controlled by said fast operating relay, means controlled by said stepping magnet for opening said locking circuit, means for repeating pulses transmitted to said fast operating relay, another relay having comparatively slow operating characteristics, said characteristics being like the operating characteristics of

5 said stepping magnet, said slow relay being controlled by said fast operating relay, means controlled by said slow relay for opening said locking circuit and means for switching from control over said stepping magnet by said fast operating relay to control over said slow relay by said fast operating relay.

6. In a telecommunication system, subscriber lines each having dial stations thereon, a selector switch for extending connections from said lines under control by said dial stations, succeeding circuits accessible to said selector switch, said selector switch having a control circuit including a comparatively fast operating relay, a locking circuit for said relay, stepping magnets for said selector switch for moving said switch in primary and secondary directions, said stepping magnets being under control by said fast operating relay, and each said magnet having means for opening said locking circuit, a cut through relay for changing the circuits of said selector switch after said stepping magnets have driven said selector switch into connection with a succeeding extended connection, a relay having operating characteristics like the operating characteristics of said stepping magnets, means controlled by said cut through relay to transfer control over said stepping magnets by said fast operating relay to control over said last relay by said fast operating relay, said last relay having means for opening said locking circuit and means controlled by said fast operating relay for repeating dial pulses into a selected succeeding circuit.

7. In a telecommunication system, subscriber lines each having dial stations thereon, a selector switch for extending connections from said lines under control by said dial stations, succeeding circuits accessible to said selector switch, said selector switch having a control circuit including a comparatively fast operating relay, a locking circuit for said relay, a primary stepping magnet for said selector switch controlled by said fast operating relay and responsive to dial pulses from one of said stations and having means for opening said locking circuit, a secondary stepping magnet for said selector switch controlled by said fast operating relay and having means for opening said locking circuit for automatically moving said switch in an idle succeeding circuit hunting operation, a cut through relay responsive to the selection of an idle succeeding circuit, a pulse correction relay having like operating characteristics to said stepping magnets, said pulse correction relay being controlled by said fast operating relay and being responsive to dial pulses from one of said stations and having means for opening said locking circuit, said cut through relay having means for transferring the control by said fast operating relay over said stepping magnets to control by said fast operating relay over said pulse correction relay and means controlled by said fast operating relay for repeating dial pulses into a said selected succeeding circuit.
